UNITED STATES PATENT OFFICE.

WILLIAM J. LONG, OF KIRKWOOD, MISSOURI.

CALENDAR.

1,323,881.

Specification of Letters Patent. Patented Dec. 2, 1919.

Application filed February 11, 1919. Serial No. 276,369.

To all whom it may concern:

Be it known that I, WILLIAM J. LONG, a citizen of the United States, residing at Kirkwood, in the county of St. Louis and State of Missouri, have invented new and useful Improvements in Calendars, of which the following is a specification.

This invention relates to calendars and has for its object the provision of a calendar of the perpetual type which is formed as a casing artistically constructed for use as a desk ornament and which includes a rotary member having inscribed thereon the names of the different months and the number of days in the month, this rotary member being movable whereby any desired month may be displayed through a sight opening in the face of the device, and further includes a web or strip bearing the numbers of the days in the month, this web being movable laterally of the device whereby the proper arrangement of the numbers of the days with respect to the names of the days for a given month may be effected.

An important object is the provision of a device of this character in which novel means is provided for moving the rotary member bearing the names of the months and also embodying a pair of rollers upon which the movable strip may be wound at either side of the device.

A further object is the provision of a calendar of this character which will be extremely simple and inexpensive in manufacture, highly efficient in use, durable in service, and a general improvement in the art.

With the above and other objects and advantages in view, the invention consists in the details of construction to be herein-after more fully described and claimed and illustrated in the accompanying drawings, in which—

Figure 1 is a front elevation of the device, Fig. 2 is a rear elevation with the rear cover removed,

Fig. 3 is a horizontal sectional view on the line 3—3 of Fig. 2,

Fig. 4 is a cross sectional view on the line 4—4 of Fig. 2, and

Fig. 5 is an elevation showing the entire strip bearing the numbers of the days.

Referring more particularly to the draw-

ing, the numeral 10 designates a rectangular casing which is provided with a suitable base 11 forming a suitable support. In the front wall the casing is provided with an opening 12 and a sheet of glass 13 is disposed against the inner face of the front wall. Disposed against the glass 13 is a panel 14 provided at its upper portion with an elongated narrow opening 15 and provided at its lower portion with a relatively large rectangular opening 16. Secured within the casing 10 rearwardly of the panel 14, is a plate 17 of less length than the casing whereby to provide openings 18 between the ends of the plate and the end walls of the casing. This plate is provided with an opening 19 to the rear of the opening 15 in the panel 14. Secured to the plate 17 are top and bottom members 20 and end members 21 which, together with the plate 17, constitute a frame disposed within the casing 10. Journalled in the top and bottom members 20 adjacent the end members 21 are vertically disposed rollers 22 to which are secured the ends of a strip 23, preferably of paper, which is divided by horizontal and vertical lines into squares within which are inscribed the numbers of the days of the months arranged as shown. Inscribed upon the panel 14 immediately above the opening 16 therein, are the names of the days of the week adapted to coöperate with the numbers on the calendar strip 23. The base 11 of the casing is provided on its underside with recesses 24 into which extend the lower ends of the rollers 22, these lower projecting ends serving as handles whereby either of the rollers may be rotated for moving the strip 23 in a horizontal direction before the panel opening 16. In actual use, the proper roller 22 is rotated so that the strip will be moved so that the first of the month may be made to fall upon any desired day of the week. The strip 23 extends from the rollers 22 through the openings 18 and travels between the panel 14 and plate 17.

Depending from the top member 20 are brackets 25 between which is journalled a horizontally disposed drum 26 upon which are inscribed the names of the months and also the number of days in each month, as clearly shown. In order to make proper

provision for leap year it is preferred that the month February be printed twice upon the drum, once with the notation, twenty-eight days and again with the notation 29 days therefor, in order that the calendar may be accurate for perpetual use. Journaled between the upper and lower members 20 of the inner frame is a vertically disposed roller 27, the lower end of which extends 10 into one of the recesses 24 and serves as a handle whereby the roller may be rotated. At its upper end the roller 27 terminates adjacent the lower edge of the drum 26 and is provided with a rubber friction disk 28 bearing against the periphery of the drum 26 adjacent one end thereof. The roller 27 does not itself extend the full height of the inner frame but is provided at its upper end with a spindle 29 which is journaled 15 in the upper member 20. By grasping the projecting lower end of the roller 27 and rotating the same, the drum 26 may be rotated so as to bring out the desired month before the openings 19 and 15 in the plate 17 and 20 panel 14, respectively.

From the foregoing description and a study of the drawings, it will be seen that upon proper manipulation of the rollers 22 and 27 the numbers of the days of the month 25 will be made to harmonize with the particular month of the year so that the device will be suited for use for every month of every year whether ordinary or leap year.

While I have shown and described the 30 preferred embodiment of my invention, it is of course to be understood that I reserve the right to make such changes in the form, construction and arrangement of parts as will not depart from the spirit of the invention or the scope of the subjoined claim.

Having thus described my invention, I claim:

A calendar comprising a casing provided in its front with a sight opening, a sheet of transparent material covering said opening, a panel disposed against the inner side of said transparent material and provided at its lower portion with a relatively large opening having inscribed at the top thereof the days of the week, said panel being further provided at its upper portion with a relatively small opening, a frame within said casing, a pair of vertically disposed rollers journaled at the ends of said frame and provided at their lower ends with reduced 45 extensions extending to the bottom of said casing whereby to serve as finger holds whereby the rollers may be rotated, a calendar web secured at its ends upon said rollers and movable before said relatively 50 large opening in said panel, a third vertically disposed roller journaled within said frame to the rear of said web, between said first named rollers and adjacent one thereof, a pair of depending brackets secured 55 upon the upper portion of said frame, a horizontally disposed roller journaled between said brackets and having its periphery inscribed with the names of the months in the year displayable selectively through the 60 relatively small opening in said panel, and a rubber disk carried at the upper end of said last named vertical roller and bearing against the periphery of said horizontal roller at one end thereof whereby upon rotation of said last named vertical roller said 65 horizontal roller may be rotated.

In testimony whereof I affix my signature.

WILLIAM J. LONG.
